UNITED STATES PATENT OFFICE

ERNST EBBINGHAUS, OF NEW YORK, N. Y.

DESIGN FOR AN AEROPLANE OR SIMILAR ARTICLE

Application filed March 15, 1929. Serial No. 30,486. Term of patent 14 years.

To all whom it may concern:

Be it known that I, ERNST EBBINGHAUS, a citizen of the German Republic, and resident of New York city, in the county of New York and State of New York, have invented a new, original, and ornamental Design for an Aeroplane or Similar Article, of which the following is a specification, reference being had therein to the accompanying drawing, forming a part hereof, in which,

Figure 1 is a top plan view of an aeroplane or similar article, showing my new design.

Figure 2 is a side elevation of the same.

Figure 3 is a front view.

I claim:

The ornamental design for an aeroplane or similar article, as shown.

In testimony whereof I hereunto affix my signature.

ERNST EBBINGHAUS.
